ABSTRACT OF THE DISCLOSURE

A display case for mercantile items having a width of about three inches or greater which comprises an enclosure having an aperture through one surface thereof. The aperture is large enough to admit a human hand and small enough to prevent withdrawal of the mercantile item therethrough. The enclosure further defines a space which is large enough to permit manipulation of the mercantile item therein by hand introduced through the aperture.

FIELD OF THE INVENTION

This invention relates to display cases, and more particularly, but not by way of limitation, to a display case which permits examination of articles contained therein but prevents unauthorized removal of the articles from the display case.

THE PRIOR ART

In the marketing of various items, such as stereo tape cartridges for use in automobiles and the like, it is common to arrange such items on shelves accessible to the public for permitting inspection of the merchandise by prospective purchasers. Due to the size of some items, such as stereo tape cartridges, it is common for a prospective purchaser to conceal the item on his person and leave the premises without paying for them.

While such items may be placed in a position inaccessible to the public, the sales expense is increased as it requires that at least one salesman be present to remove the merchandise from the enclosure within which it is stored to permit inspection by prospective customers. It is also necessary that the salesman remain in attendance while the customer is examining the merchandise.

SUMMARY

The present invention provides a display case which will permit inspection of merchandise such as stereo tape cartridges by prospective customers without a salesman being present, but which will prevent unauthorized removal of the merchandise from the display case.

The invention may be generally described as a case for displaying mercantile items having a width of about three inches or greater. The case includes an enclosure provided with an aperture through one surface thereof, the aperture being large enough to admit a human hand but small enough to prevent withdrawal of the mercantile item therethrough. The enclosure also defines a space therein which is large enough to permit manipulation of the mercantile item therein by a hand introduced through the aperture.

To be more specific, reference is here made to the drawings, in which:

FIGURE 1 is a front perspective view, partially cut away, of one embodiment of the present invention;

FIGURE 2 is a side perspective view of yet another embodiment of the present invention; and

FIGURE 3 is a rear view, partially cut away, of the embodiment of the invention illustrated in FIGURE 2.

THE PREFERRED EMBODIMENTS

With reference to FIGURE 1, the display case 10 comprises a first box-like member 11 to the face 12 of which

2

is affixed a transparent plastic sheet 13. The sheet is affixed by a plurality of screws 14 or the like disposed about the periphery of sheet 13. Display case 10 includes means for supporting mercantile items, and the means in the embodiment of FIGURE 1 take the form of a plurality of shelves 16 supported by support members 18 which are disposed between and affixed to top and bottom walls 19 and 21 of box-like member 11. To permit access to the items stored on shelves 16, which, for example, may be stereo tape cartridges, transparent sheet 13 is provided with a plurality of apertures 22 which are large enough in diameter to permit a human hand to be extended through the aperture for removing an item from one of the shelves 16.

To permit inspection of the merchandise supported on shelves 16 by a prospective customer, box-like enclosure 11 and sheet 13 define a space 23 therebetween which is large enough to permit manipulation of the item stored on shelves 16 so that the customer may view all surfaces of the item.

To stock shelves 16 or remove an item from them for sale to a customer, the back of box-like member 11 (not illustrated in FIGURE 1) of display case 10 is pivotally mounted thereto by hinges 24 to permit sales personnel to gain access to the shelves 16 by way of the back of the display case 10.

With reference to FIGURE 2, which illustrates yet another embodiment of the invention, a box-like member 25 mates with yet another box-like member 26 constructed of a transparent material such as a plastic or the like. Member 26 is slightly larger in dimension than member 25 permitting members 25 and 26 to mate and be affixed in a fronting relationship by a plurality of screws 27. As illustrated in FIGURES 2 and 3, box-like member 25 has a back wall 28 which is connected to one edge of rectangular frame 29 by hinges 31 and 32 by means of screws 33 or the like. The opposite edge of back wall 28 is affixed to the adjacent wall of rectangular member 29 by a conventional spring bias latch assembly 34. One portion 35 of latch 34 is affixed to back wall 28 and the other portion 36 is affixed to wall 37 of rectangular member 29. This embodiment of the invention, as particularly illustrated in FIGURE 3, also carries a plurality of shelves 38 which are supported by vertical supports 41. Supports 41 are disposed between and affixed to the top and bottom rectangular member 29 by any conventional means.

By operation of latch 34, a salesman may place items on shelves 38 of the embodiment illustrated in FIGURES 2 and 3 for subsequent inspection by prospective customers. The prospective customer by extending a hand through one of the apertures 42 in the transparent box-like member 26 may remove an item from one of the shelves 38. The item once removed from shelves 38 may be manipulated within space 43, and if the item meets with his approval may summon a salesman to have it removed for him.

The items, whether displayed in the embodiment illustrated in FIGURE 1 or the embodiment illustrated in FIGURES 2 and 3, will, of necessity, be of a width greater than about three inches to prevent their removal from the display case, since the apertures 22 in FIGURE 1 and 42 in the FIGURES 2 and 3 embodiment must be on the order of two and one-half to three inches in diameter to readily admit a human hand. Stereo tape cartridges, which normally are four inches wide, five inches long and one inch thick may be conveniently displayed in either of the illustrated embodiments.

Various materials may be used in constructing a display case in accordance with the present invention, and the embodiments illustrated are intended to be only representative.

For example, the surface provided with the aperture may comprise a wire mesh having either round or square apertures of a size to admit a human hand, but prevent withdrawal of mercantile items. It will also be clear that the front panel 13 in the FIGURE 1 embodiment or its counterpart the box-like member 26 in the FIGURE 2 embodiment could be connected to the remainder of the display case by hinges or the like and provided with a suitable lock to permit access by authorized personnel. Such a structure would, of course, eliminate the need for a latch and hinges at the back of the display case. Various other modifications will undoubtedly occur to those skilled in the art.

Further, while rather specific terms have been used in describing two embodiments of the invention, they are not intended, nor should they be construed as a limitation upon the invention as defined by the following claims.

What is claimed is:

1. A case for displaying a plurality of mercantile items each having a width of about three inches or greater, comprising:

an enclosure provided with a plurality of apertures through one wall thereof, said apertures being large enough to admit a human hand and small enough to prevent withdrawal of the mercantile item therethrough; and

plural means each for supporting one of said mercantile items within said enclosure, said enclosure defining a space between said means for supporting said mercantile items and the one wall having the apertures, which space is large enough to permit one of said items to be grasped and withdrawn into said space for manipulation by a hand extended through one of said apertures.

2. The article of claim 1 wherein the surface provided with the aperture is formed of a transparent material.

3. The article of claim 1 wherein said enclosure is a six sided polyhedron having front and back walls, said front wall is provided with the aperture, said means for supporting said article with said enclosure comprises a shelf supported between side walls of said enclosure and positioned proximate said rear wall, and said article includes: means for permitting access to said enclosure through said rear wall.

4. The article of claim 3, wherein said means for permitting access to said enclosure through said rear wall comprises:

at least one hinge joining one edge of said back wall to an adjacent wall of said enclosure; and

latch means joining the opposite edge of said back wall to an adjacent opposite wall of said enclosure.

5. The article of claim 1, wherein enclosure comprises: a first transparent box-like portion having an open side; a second box-like portion having an open side which mates with the first box-like portion to form a six sided polyhedron having a front wall and a back wall, the front wall being formed by said first box-like portion and having said aperture therein and the back wall being a portion of said second box-like portion; and

means affixing said first and second box-like portions together.

6. The article of claim 5, wherein said means for supporting said mercantile article comprises:

a shelf supported by said second box-like member.

7. The article of claim 6, which includes: means for permitting access to said enclosure through said rear wall.

8. The article of claim 7, wherein the means for permitting access to said enclosure through said rear wall comprises:

at least one hinge joining one edge of the back wall to an adjacent wall of said second box-like member; and

latch means joining the opposite edge of said back wall to an adjacent opposite wall of said enclosure.

9. The article of claim 8 wherein said front wall is provided with a plurality of said apertures and said second box-like portion supports a plurality of shelves.

10. A display case for utilization in theftproof merchandising of record tape cartridges of generally standardized size and dimension, comprising:

enclosure means having at least one wall thereof formed from transparent material and having a plurality of apertures formed through said one wall in spaced apart relationship, each of said apertures being large enough to admit a human hand but small enough to prevent withdrawal of one of said record tape cartridges;

support shelving means disposed within said enclosure, said support shelving means being located to support one or more of said record tape cartridges within continuous view through said transparent one wall, said enclosure also defining a space between said support shelving means and said transparent one wall which space is large enough to permit said record tape cartridges to be grasped and manipulated by one or more hands as extended through selected one or more of said apertures.

11. A display case as set forth in claim 10 which is further characterized in that:

a selected wall of said enclosure is hingedly affixed within said enclosure and capable of being open to provide access to said enclosure; and

locking means affixed on said enclosure for selectively locking said hingedly affixed wall in the closed position.
